UNITED STATES PATENT OFFICE.

CHRISTOPHER FLINN, OF MILTON, PENNSYLVANIA, ASSIGNOR TO AMERICAN CAR AND FOUNDRY COMPANY, OF NEW YORK, N. Y., A CORPORATION OF NEW JERSEY.

METHOD OF STRAIGHTENING SHEET METAL.

Application filed May 27, 1920. Serial No. 384,651.

To all whom it may concern:

Be it known that I, CHRISTOPHER FLINN, residing at Milton, Northumberland County, Pennsylvania, and being a citizen of the 5 United States, have invented certain new and useful Improvements in Methods of Straightening Sheet Metal, of which the following is a full, clear, and exact description, such as will enable others skilled in the art 10 to which it appertains to make and to use the same, reference being had to the accompanying drawings, which illustrate the preferred form of the invention, though it is to be understood that the invention is not 15 limited to the exact details of construction shown and described, as it is obvious that various modifications thereof within the scope of the claims will occur to persons skilled in the art.

20 In said drawings:

Figure 1 is a view in elevation showing the die blocks with the dies positioned to press the tapered rib in a plate and a plate between the dies with the rib pressed 25 therein;

Figure 2 is partly a central vertical section of Fig. 1 and partly an end elevation of the upper die block;

Figure 3 is a view, similar to Fig. 1, showing the dies reversed so as to press out the 30 rib pressed in the plate;

Figure 4 shows a plate before the tapered rib has been pressed in it; with the rib pressed in it; and after the rib has been 35 pressed out;

Figure 5 is a plan view of a long plate with the tapered ribs pressed in; and

Figure 6 is a side elevation of the plate shown in Figure 5.

40 It is an object of my invention to provide a new and improved method of removing the camber from sheet metal plates by pressing a tapered rib across the plate from the inside of the camber so as to stretch that 45 portion of the plate and then to press out the tapered rib leaving the plate flat.

For carrying out my process I have provided die holding blocks 1 and 2, the rocking die holding block 1 being attached to the top die holding block 3 by a pin 4 which passes through an opening in the block 1 and through openings in the lugs 5 on the block 3. The block 3 is adapted to be attached to the moving head of a punching 55 machine or press while the block 2 is adapted

to be mounted on the base or bed plate of the machine. The die holding blocks 1 and 2 are provided with openings that receive the dies 6 and 7, stop pins 8 being provided to hold the dies in position in the holding 60 blocks.

As shown in Fig. 1, the bottom die is provided with the projection 9 that forms the tapered rib across the plate while the top die is provided with a recess 10 to cooperate with 65 the projection 9 on the lower die.

In operation, the dies are placed in position in the die holding blocks as shown in Fig. 1 and the plate placed on the dies so that tapered rib will be pressed in the plate 70 with the pointed end of the rib on a line with the beginning of the camber in the plate, and the rib extending with the camber to the edge of the plate. Pressing the tapered rib in the plate provides for a 75 graduated stretching of the plate that is greatest where the camber is greatest and which tapers off to nothing on the line at which the camber begins.

After the tapered rib has been pressed in 80 the plate the plate is removed and the dies are withdrawn, turned to the position shown in Fig. 3 and inserted in the openings in the die holding blocks. The plate is then inserted between the dies and the rib pressed 85 out leaving the plate flat. While in Fig. 4 but one rib has been shown as pressed in the plate, in the case of longer plates two or more ribs can be made, each serving to correct the camber in a portion of the plate 90 when pressed out.

In the case of the long plate shown in Figs. 5 and 6, it will be noted that the edges A—B and C—D are slightly curved so that the middle point of a straight line joining the ends of the edge C—D of the plate of the standard length of 33 feet would be displaced approximately 1 inch from the edge C—D. To correct the camber in the plate as shown, several ribs would have to be pressed into the plate and then pressed out, some for instance, extending as shown from the edge A—B to the edge C—D while others would extend from points between the edges to the edge C—D, the number of ribs and the extent to which they extend to the edge C—D into the plate depending on the amount of camber to be corrected in the section of plate adjacent to the rib. The 100 distance the point of the rib is from the edge 105 110

C—D is considered as the length of the camber and the line at which the point of the rib is, is considered as the line of origin of the camber of that section of the plate.

5. What I claim is:

1. The method of removing the camber from a plate which consists in forming a tapered rib in the plate so as to stretch the plate and then pressing out the rib.
- 10 2. The method of removing the camber from a plate which consists in pressing in the plate a tapered rib of the length of the camber and then pressing out the rib.
- 15 3. The method of removing the camber from a plate which consists in pressing a tapered rib in the plate, the rib being disposed with its pointed end at the line of origin of the camber and then pressing out the rib.
- 20 4. The method of removing the camber from a plate which consists in pressing a

tapered rib in the plate, the rib being disposed with its pointed end at the line of origin of the camber and extending to the plate edge, and then pressing out the rib. 25

5. The method of removing the camber from a plate which consists in pressing a tapered rib in said plate the rib being disposed with its point of greatest depression at the plate edge, and pressing out said rib. 30

6. The method of removing the camber from a plate which consists in pressing a tapered rib in said plate so as to stretch the plate in proportion to the degree of camber and pressing out said rib to leave said plate flat. 35

In witness whereof I have hereunto set my hand in the presence of two witnesses.

CHRISTOPHER FLINN.
